WILLIAM N. WHITELEY AND THOMAS HARDING, OF SPRINGFIELD, OHIO.

Letters Patent No. 79,171, dated June 23, 1868.

IMPROVEMENT IN HARVESTER DRIVING-WHEELS.

The Schedule referred to in these Letters Patent and making part of the same.

TO ALL WHOM IT MAY CONCERN:

Be it known that we, WILLIAM N. WHITELEY and THOMAS HARDING, of Springfield, in the county of Clark, and State of Ohio, have invented a new and useful Improvement in Adjustment for Harvesters' Driving-Wheels, &c.; and we do hereby declare the following to be a full, clear, and exact description of the same, reference being had to the accompanying drawings, in which—

Figure 1 is a side elevation of a part of a harvesting-machine, showing the operation of our invention.

Figure 2 shows in elevation the axle of the driving-wheel detached.

Figure 3 is a vertical longitudinal section through hub and axle.

This invention consists in making the spindle or axle of a gear-wheel adjustable upon a centre, eccentric to the axis of said spindle, so that by turning said spindle upon said centre, the axis of the spindle may be changed in position, and the mesh of the gear-wheel with its pinion may be adjusted.

In the drawings and description, this device is represented as attached to a harvesting-machine, but we do not intend to limit ourselves to its use in connection with those machines, nor to the precise details of construction herein shown and described, as it will appear evident that they may be greatly changed without departing from the spirit of our invention.

That others may understand the construction and operation of this invention, we will particularly describe it.

A is the main wheel of a harvester, and B is the gear-ring, cast with it, or cast separately and afterwards fitted and secured to the spokes of the wheel A. Owing to well-known reasons, castings made from the same pattern will seldom be of equal size when cold, and this variation in such castings as harvesters' driving-wheels is sufficient to affect the mesh and working of the gears materially, and it is necessary either to let the machines go out with this imperfection, or to provide some mode of compensation. It is not convenient to gauge the distances for the centres of the shafts in every case, and if this should be done, the wheels could never be interchangeable, and it is costly to construct adjustable boxes for the bearings, as well as inconvenient to the user. We therefore construct the hollow axle C, in such a manner that the hollow through which the clamping-bolt D passes, shall be a little eccentric to the cylindrical outer surface of said axle, upon which the wheel A runs. A flange, E, surrounds the base of this axle, to give it a strong and steady bearing upon the surface of the coupling-arm F, and a slightly projecting stud, I, concentric with the clamping-bolt D, fits into a corresponding socket in the face of the coupling-arm, to give the axle a constant and true centre, without depending upon the bolt D for that purpose. The flange E is concentric with the stud I, and in its edge we make a number of notches, G, and at a proper point on the surface of the coupling-arm, we fix a pin, H, so that it may engage with either one of said notches. Now, when the wheel A is to be put in place, the axle C is turned around on the bolt D, until the teeth of the wheel B engage properly with the teeth of its pinion, and the nearest notch G is then brought to the pin H, and the axle is secured in that position. The red lines in the drawings fully illustrate the change in the distance between the centres of the wheel and pinion which can readily be produced by this arrangement.

If at any time it is necessary to change wheels, or to replace an old one with a new one, it will be necessary to change this adjustment, and the farmer or attendant can always effect it without trouble, and in the manufactory it will be of the greatest convenience in adjusting the machines for the market. At present there is very rarely any attempt to secure an adjustment of these parts, and as a consequence but few machines in the market are correctly and accurately fitted in that respect.

Having described our invention, what we claim as new, is—

The eccentric hollow axle C, provided with the stud I, or its equivalent, and the notched flange E in connection with a pin, H, socketed coupling-arm F, and bolt D, substantially as and for the purpose set forth.

WM. N. WHITELEY,
THOMAS HARDING.
